UNITED STATES PATENT OFFICE.

HERBERT LESLIE HOBDAY AND FREDERICK WILLIAM NUNN, OF MELBOURNE,
VICTORIA, AUSTRALIA.

APPARATUS FOR CASTING DENTAL PLATES IN METAL.

Application filed May 9, 1922. Serial No. 559,542.

To all whom it may concern:

Be it known that HERBERT LESLIE HOBDAY and FREDERICK WILLIAM NUNN, subjects of the King of Great Britain, residing 5 at 90 Collins Street, Melbourne, in the State of Victoria, Commonwealth of Australia, have invented a certain new and useful Improved Apparatus for Casting Dental Plates in Metal, of which the following is a specification.

Our invention relates to an improved apparatus for casting dental plates made of gold and other metals, which hitherto have been formed either by swaging, the application 15 of compressed air, or by subjecting the molten metal in the investment to steam pressure to force the metal into the cavity or mould.

According to our invention, a wax plate is 20 made from the impression taken from the patient and is invested in a cylinder or pot in the usual way. After burning out the wax, gold or other metal to form the plate is reduced to a molten condition on the 25 top of the cylinder or pot and over the sprue or channel between the metal and the mould. The pot is held upon the end of a rigid rod secured to and depending from a rotatable horizontal spindle and upon the pot being 30 swung around with the rotating spindle several times at a fair rate of speed, the molten metal will be forced into the mould to form the plate. It is important to rigidly secure the bar to the spindle to insure that 35 the investment shall truly rotate in a circle in a vertical plane.

Further, by employing centrifugal force in the way suggested, an excellent pressure is obtained in a line approximately that of 40 the axis of the rigid suspension bar and the molten metal is caused to flow into every part of the mould which will be solidly filled, thus leaving, when cool, a satisfactorily dental plate.

45 The rigid depending rod carrying the investment cylinder or pot is preferably counterweighted, and the rotatable spindle can be actuated through a sprocket and chain gearing or other suitable and convenient 50 driving means.

The investment pot can be formed of metal or of a refractory material and is perforated in the sides. It is held in a basket that may be fitted with a socket member which 55 in turn, can be provided with liners to ac-

commodate various sized investment pots. Means are provided for the ingress and egress of the pot from the basket.

But in order to fully understand our said invention, reference is made to the accompanying drawings, in which—

Figure 1 is a perspective view of the machine.

Figure 2 a detail sectional plan view of the basket and fittings for holding the investment, and

Figure 3 is a sectional elevation of the same.

Between the stout cheeks of the machine the horizontal spindle 3 is mounted and which can be driven through the usual sprocket and chain gearing 4. Depending from the spindle 3, to which it is securely attached, is a stout rod 5 upon the lower end of which the investment cylinder basket 6 is hung. This basket is conveniently constructed of two metal straps placed at right angles, the one to the other, and is brazed to the rod 5. To the lower extremities of the basket 6 a ring 7 is riveted, the ring being provided with bayonet joints. Fitting easily within this ring is a socket plate 9 into which fits a hollow flanged plate 10. In the hollow or central part of this plate an investment pot 11 of comparatively small diameter, such as might be employed in the investment of smaller work, is vertically held (as shown in Fig. 2), while on the outside of the flange a larger investment cylinder 11a can be accommodated (as in Figs. 2 and 3). A still larger cylinder, such as would be used in the large work, can be inserted and held within and against the turned up edge of the socket plate 9, on which are pins 12 adapted to fit the bayonet joint in the ring. Thus, by means of the parts described, investment pots of various diameters can be satisfactorily held in the basket. To insert or remove the same from the basket, the pins 12 are moved in the joints and the socket plate 9 withdrawn together with the supported parts.

The pots or cylinders holding the investment are perforated in the sides to facilitate the same heating quickly and evenly when placed over a burner to reduce the wax plate.

The rod 5 is provided upon the opposite side of the spindle 3 with a counter-weight 8 which assists in the smooth working of the machine when the basket is swung.

In the case of very small work, such as the casting of inlays, the plate 10 can be made with a smaller central opening, there being two or more such plates for selection 5 for use in the socket member 9.

Having now described our invention what we claim as new and desire to secure by Letters Patent is:—

In a machine for casting dental plates, a 10 basket on the end of a rigid rod secured to and depending from a rotatable spindle, a

ring secured to the lower part of the basket sides, bayonet joints in the ring, a socket plate arranged in and detachably connected to the ring, and a hollow flanged member fitting within the socket plate and arranged to accommodate investment pots of varying diameters. 15

In testimony whereof we affix our signatures.

HERBERT LESLIE HOBDAY.
FREDERICK WILLIAM NUNN.
